UNITED STATES PATENT OFFICE.

EMILY D. LOWRY, OF PHILADELPHIA, PENNSYLVANIA.

TELEPHONE.

1,179,117.

Specification of Letters Patent. Patented Apr. 11, 1916.

Application filed April 16, 1915. Serial No. 21,671.

To all whom it may concern:

Be it known that I, EMILY D. LOWRY, a citizen of the United States, residing in the city of Philadelphia, county of Philadelphia, 5 and State of Pennsylvania, have invented certain Improvements in Telephones, of which the following is a specification.

My invention relates more particularly to telephone receivers and its primary object is 10 to provide receivers with sound amplifying means of novel character, readily applicable to usual constructions, whereby the sounds are rendered louder, clearer and audible at a distance.

15 A receiver having my improvements applied thereto can be laid down and the person receiving the message left at liberty to write or record the communication, the usual message being audible in any part of a room

20 of ordinary size containing the receiver provided with my improved attachment. This attachment, in the present preferred form, comprises a supplemental diaphragm having means for connecting it to the ear cup of

25 the receiver, a pin or strut connecting it with the receiver diaphragm, and a short horn or sound tube through which the vibrations are transmitted.

The characteristic features of my improvements will more fully appear by reference to 30 the following description and the accompanying drawings in illustration thereof.

In the drawings, Figure 1 is a part sectional side elevation of a telephone receiver 35 having my attachment applied thereto; Fig. 2 is a part sectional side elevation of the attachment; and Fig. 3 is an end view of the same.

The mechanism shown in the drawing by 40 way of illustrating one of the forms of my invention comprises a usual telephone receiver 1 having the ear cup 2 with the ring 3 thereon and the diaphragm 4 thereon, in combination with the sound tube 5 having the rim 6 which telescopes on the ring 3, the spring clips 7 which engage the ring to hold the rim in place, the ring 8 which screws into the tube, the auxiliary diaphragm 9 carried by the ring 8, and the pin or strut 10 fixed 45 to the center of the auxiliary diaphragm.

It will be understood that the electrically or electro-magnetically induced vibrations of the main diaphragm 4 by the coil or electro-magnet 4' are communicated to the diaphragm 9 through the pin or strut 10 and 55 also through the air between the diaphragms, the resulting amplified vibrations being transmitted through the sound tube 5 by which they are further amplified.

The attachment can be retained upon the 60 receiver to which it is applied or temporarily connected for special use, as it is adapted to be applied and detached readily.

The rim or socket 6 and clips 7 can be sprung to effect their accommodation to different rings 3 and the ring 8 can be adjusted within the tube 5 to provide the proper relation between the diaphragm 4 and the strut 10.

The attachment can be carried about and 70 applied at will to any usual receiver from which amplified sounds are desired.

Having described my invention, I claim:

1. The combination with a telephone receiver having a diaphragm subject to a magnetic field, an auxiliary diaphragm for directly producing sound waves, and a strut 75 positively connecting said diaphragms.

2. The combination with a telephone receiver having a diaphragm subject to a magnetic field, an auxiliary diaphragm for directly producing sound waves, means for detachably connecting said auxiliary diaphragm, and a strut for positively connecting 80 said diaphragms.

3. The combination with a telephone receiver having a diaphragm subject to a magnetic field, a device having a diaphragm for directly producing sound waves and clips for engaging said receiver, and a strut for 90 positively connecting said diaphragms.

In testimony whereof I have hereunto set my name this 13th day of April, 1915, in the presence of the subscribing witnesses.

EMILY D. LOWRY.

Witnesses:

Jos. G. DENNY, Jr.,
